UNITED STATES PATENT OFFICE.

FRED. L. ADAMS, OF PROPHETSTOWN, ILLINOIS, ASSIGNOR OF ONE-HALF TO
JOHN F. KILROY, OF SAME PLACE.

CHECKREIN-HOOK.

SPECIFICATION forming part of Letters Patent No. 444,264, dated January 6, 1891.

Application filed August 27, 1890. Serial No. 363,197. (No model.)

To all whom it may concern:

Be it known that I, FRED. L. ADAMS, a citizen of the United States, residing at Prophets-town, in the county of Whiteside and State 5 of Illinois, have invented a new and useful Checkrein-Hook, of which the following is a specification.

This invention has relation the checkrein-hooks; and the objects in view are to provide 10 a hook adapted to permit of a ready withdrawal and introduction of the checkrein, and yet at the same time absolutely prevent any accidental disconnection of the two, said hook being of simple and economical construction 15 and consisting of but few essential parts.

With the above objects in view the invention consists in certain features of construction hereinafter specified, and particularly pointed out in the claim.

20 Referring to the drawings, Figure 1 is a side elevation of the hook constructed in accordance with my invention. Fig. 2 is a transverse section through the saddle-plate and connecting-bolt. Fig. 3 is a longitudinal section, and Fig. 4 a detail in perspective of the bolt and spring-tongue mounted thereon.

Like numerals of reference indicate like parts in all the figures of the drawings.

1 designates the usual saddle-plate, which 30 in the present instance is provided near its front end with a square opening 2.

3 designates the bolt, introduced vertically through the opening and adapted to pass through the saddle-tree 4 of the harness-saddle. The lower end of the bolt is threaded, as usual, and after passing through the rear end of the check-hook 5 is secured in position by means of a binding-nut 6, which binds the saddle-tree, hook, and saddle-plate snugly together. The upper end of the bolt is provided with a square or angular head 8, which somewhat snugly fits the square opening 2 of the saddle-plate, and upon the head is mounted a rectangular plate 9, provided at its ends 40 with flanges 10, upwardly disposed and connected by a transverse pintle 11. A piece of

spring-wire is bent upon itself to form a central tongue 12 and straddles the pintle at its center, said tongue being upwardly disposed and terminating close to the under side of 50 the rearwardly-curved checkrein-hook. The terminals of the wire are coiled loosely about the pintle at each side of the tongue, as shown at 14, the disposition of the coils being reversed to each other, so that the one neutralizes 55 the other and the tongue is held in a perfectly vertical position, but capable of being depressed either to the front or to the rear. The ends of the coils lie flat upon the plate at opposite sides of the pintle. It will now 60 be observed that a checkrein will be readily inserted in the hook and forced by the spring-tongue in either direction, which latter will readily yield to any pressure greater than that calculated to accidentally disconnect the 65 checkrein. It will thus be seen that I utilize for the support of the spring-tongue the bolt employed to connect the saddle plate, tree, and check-hook.

Having described my invention, what I 70 claim is—

The combination, with a saddle-plate having a rectangular opening in its front end and a check-hook located under the opening, of a bolt having a square head mounted in the 75 opening, depending through the opening and through the checkrein-hook, an oblong plate mounted upon the upper end of the bolt under the hook and having opposite flanges, a pintle connecting the flanges, and a spring-wire bent at its center to form a tongue and having its terminals coiled in reverse directions around the pintle and bearing upon said plate at opposite sides of the pintle, substantially as specified.

In testimony that I claim the foregoing as my own I have hereto affixed my signature in presence of two witnesses.

FRED. L. ADAMS.
